United States Patent Office.

W. H. MITCHELL AND J. F. MITCHELL, OF MACOMB, ILLINOIS.

Letters Patent No. 82,862, dated October 6, 1868.

IMPROVEMENT IN BROADCAST SEED-SOWER.

The Schedule referred to in these Letters Patent and making part of the same.

TO ALL WHOM IT MAY CONCERN:

Be it known that we, W. H. MITCHELL and J. F. MITCHELL, of Macomb, in the county of McDonough, and State of Illinois, have invented certain new and useful Improvements in Broadcast Seed-Sowers; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention relates to certain improvements in that class of machines used for sowing small grains broadcast; and the invention consists—

First, in a device for stirring the grain in the hopper to prevent clogging.

Second, in a novel construction of the scattering-device, and

Third, in a novel arrangement of the slides for regulating the feed, as hereinafter more fully explained.

Figure 1 is a top plan view of the machine, and

Figure 2 is a vertical section, taken on the line $x-x$ of fig. 1.

In constructing our improved machine, we first provide a frame, consisting of two horizontal pieces, C B, united at their back by a vertical piece, A, upon the top of which, at one end, is mounted a hopper, H, as usual in these machines. At the opposite end, we mount a vertical shaft, T, having a series of pulleys, P, attached, as represented in fig. 2. To this shaft we secure a compound or double crank, R, with a handle, b, for operating it. To the neck e of this crank we connect a couple of wires or small rods, c, which extend to and pass through small holes in the side of the hopper H, and having their ends terminate near the centre of the hopper, over the orifice o, through which the grain is fed, as shown more clearly in fig. 1. It will be seen that when the crank is turned, these rods c will be moved around with the neck e at their outer ends, thereby imparting to their inner ends a continuous and corresponding movement, thus keeping the grain stirred up, and effectually preventing its clogging, and causing it to feed with regularity and an even flow.

The form of the mouth or orifice through which the grain passes from the hopper to the scatterer is represented by o, fig. 1, and upon the piece C are secured two slides or gates, h and f, as shown in fig. 1. These slides are so arranged that each one will close one-half of the orifice when shoved in, and, as each can be moved independent of the other, the orifice can be closed on one side or the other to one-half its extent or capacity, as may be desired, or, by shoving in both together, it may be closed entirely, and thus shut off the flow of the grain entirely. By this arrangement of the slides, the grain may be fed down at either side of the shaft G into the scatterer L, as desired, and the orifice can also be adjusted to adapt the machine to sowing different kinds of grain, and to regulating the quantity at will.

Our improved scatterer or distributer consists of a piece of sheet metal, having a hole cut in its centre of proper size to admit the shaft G up to the shoulder n, to which it is firmly secured by screws, or in any suitable manner. The sides are then bent up and brought together at the top for some distance from each end, thus forming two tubular spouts, tapering towards their outer ends, which are left open.

Around the shaft G, at the top, the distributer is cut away, as shown at m, fig. 2, and by the dotted line in fig. 1, to form an opening into or through which the grain falls as it passes from the hopper. The distributer is driven by a cord from the pulley P, and, as the grain falls into the distributer, the centrifugal motion of the latter scatters it evenly over the ground.

The grain is fed to the hopper H through a flexible tube, O, which is attached to the hopper by a sleeve, I, having slots, l, cut in it, and engaging over pins, a, as shown in fig. 2. The frame is provided at its ends with knobs, i, to which straps are fastened, for holding it upon the body of the person using it.

By these improvements, we are enabled to produce a machine that operates in superior manner.

Having thus described our invention, what we claim, is—

1. The stirrers c, operated by the compound crank R, when arranged to operate substantially as described.
2. The distributer L, constructed and arranged to operate substantially as set forth.
3. The two slides, h and f, arranged to be operated independently or jointly, as herein described.

W. H. MITCHELL.
